UNITED STATES PATENT OFFICE

117,781

DESIGN FOR A RAIL BOND TERMINAL

Homer P. Chandler, Mansfield, Ohio

Application March 4, 1939, Serial No. 83,342

Term of patent 14 years

To all whom it may concern:

Be it known that I, Homer P. Chandler, a citizen of the United States, residing at Mansfield, in the county of Richland and State of Ohio, have invented a new, original, and ornamental Design for Rail Bond Terminals, of which the following is a specification, reference being had to the accompanying drawing, forming a part thereof.

In the drawing:

Fig. 1 is a side elevational view, Fig. 2 is a top plan view, Fig. 3 is a bottom plan view, and Fig. 4 is an end view of a rail bond terminal, showing my new design.

I claim:

The ornamental design for a rail bond terminal, as shown.

HOMER P. CHANDLER.
